JORDAN PLUG JACKET

Oscar E. Larson, Andover, Mass., assignor to John W. Bolton & Sons, Inc., Lawrence, Mass., a corporation of Massachusetts

Application January 23, 1946, Serial No. 642,918

11 Claims. (Cl. 92—27)

1

This invention relates to what are known as the linings for Jordan engines. It has particular reference to the outside linings or jackets of the type which can be slipped on a frustro-conical Jordan plug but many of its features are suitable for the inside lining for a Jordan shell.

The cutting members known as knives generally used in a shell lining are bent although in some cases straight knives or cutting members are used, while ordinarily the bars or cutting members used on the outside of a Jordan plug are straight.

Linings or jackets for Jordan plugs have been cast of a single metal and have been made by stringing the bars on rods or wires which pass through holes, the spaces between the bars being filled with wood or some sort of plastic but there are objections to the cast jackets and also to the wire strung jackets. The stretching of the metal wire is a factor which causes great difficulty and often loosens parts of the jacket causing smashes.

Instead of the wire near the inside, I use a series of disks with cut out portions in which the bars rest thus providing not only greater strength near the outside to resist sideways shock but more metal to resist such stretching of the wire. These disks may be used over and over as they are not easily distorted nor damaged and they do not wear out as rapidly as the bars.

If a plastic is used between the bars or even if wooden separators are used, when a bar hits a metal obstacle or obstruction such as are sometimes encountered, it bends over and distorts the separating means to an objectionable extent.

In this invention, I use a plurality of parallel annular metal disks, each with a plurality of radial outside bar cut outs extending inward and with aligned inside bar or tongue cut outs extending outward with the connecting metal of the disk between them. I provide each bar with a plurality of inside L shaped recesses which form tongues, the bar holding or connecting part of the disk between an inside and an outside cut out fitting into the recessed part of a bar, the tongue extending under it and thereby being locked against radially outward movement.

If this connecting part of a disk fits into the arm of a recess in a bar with a close fit or if the inner and outer faces of such arm converge so that there is a wedging action, the whole assembly is built up and locked together without the necessity of welding or riveting. Such a structure can be used in some cases with no filling in the pockets formed between the disks and the bars, but preferably these pockets are filled with

2

wood or plastic at least part way up to the outer rims of the disks. The pockets may however be filled up to the outer edges of the bars.

As part of the preferred type of my plug jacket, I provide two or more, preferably 4, 6, or 8, extra deep bars of such a depth that they project inwardly beyond the inner edges of the rest of the bars and I provide a plug with slots corresponding in number, size and position to these inwardly projecting deep bars so that, as shown and described to a certain extent in patent to Schueler, No. 2,336,039, the complete jacket or lining can be slipped on a plug having a number of slots corresponding with the number of inwardly projecting deep bars whereby the whole jacket is prevented from turning on the plug and these inwardly projecting bars also act as locks to counteract centrifugal force.

With this disk construction, there is a much greater amount of holding metal extending radially outward in the disks than where there are merely wire rods or bands to hold the bars and separators against centrifugal force, the outside cut outs in the disks also prevent the bars from tipping over circumferentially when an obstacle is encountered and the metal between the inside and outside cut outs keeps each disk perpendicular to the axis of the assembly.

The bars and disks may be forced together so that the combination is rigid and in this condition it can be used in some cases without any separators. Moreover, if one or more bars are bent or otherwise injured, such bar or bars can be driven out and can be replaced by a new bar or bars. The life of the unit is therefore prolonged.

In the drawings, Fig. 1 is an isometric view of one type of Jordan engine plug with a lining or jacket of my construction shown as slipped part way onto it.

Fig. 2 is an enlarged view as from the large end of a plug and lining such as shown in Fig. 1, partly broken away to show the construction.

Fig. 3 is an elevational view of a disk such as used in the construction shown in all of the views and Fig. 4 is a side elevation on a small scale showing a typical plug bar or cutting member of the type such as shown in substantially all of the views.

Fig. 5 is a sectional view on a longitudinal vertical plane of a lining or jacket such as shown in Figs. 1 and 2.

Fig. 6 is a detail view showing the side of a bar with a disk for supporting it, the relation between

the holding part of the disk and the bar being of the preferred type.

Figs. 7 and 8 are views on planes which extend at right angles to the axis of the lining and pass through holes in a bar.

Figs. 9, 10, 11 and 12 are views similar to Fig. 6, showing diagrammatically other modifications of the tongues on the bars and of their relation to the holding part of disks.

Fig. 13 is a detail of larger size than Fig. 8, showing certain bars and disks with precut separators.

Fig. 14 is a view similar to Fig. 13 but showing a somewhat different arrangement of bars and disks.

Fig. 15 is a longitudinal view along the face of a precut wooden separator fastened in place in a particular way.

In the drawings, L represents the complete lining or jacket for a Jordan engine plug P around the outside surface of which are a plurality of bar holding slots 40, 40. As shown, there are eight slots marked 40 to receive eight bars C, which are somewhat deeper than the others marked B to hold the assembly together and to prevent the lining from turning.

S represents the shaft which carries plug P.

D, D, represent annular disks each preferably made of metal, each with parallel faces 13 and 14 and each with an outside rim 16 and an inside rim 17.

Extending radially inward from its outside rim 16 are a plurality of outside radial bar cut outs 12 which extend radially inward and from the inside rim 17, the inside radial bar cut outs 11 extend radially outward each in line with an outside bar cut out 12. Between the inside and outside radial cut outs there is a bar holding portion 15.

I use a plurality of substantially straight bars represented generally by B and by C each positioned partly in an aligned outside disk cut out 12 and each having a tongue 6 extending down inside the disk-tongue holding portion 15 and into the inside cut out 11.

Each bar as shown has a reduced tip or shoulder 64 at one end and a slot 65 at the other end. A ring 63 around tips 64 and a ring 62 seated in slots 65 help to steady the ends of the bars but they are not absolutely necessary.

These tongues 6 are formed by L-shaped recesses 5 which extend from the inside edge 1 of each bar at a slightly obtuse angle at 20 and thence at 21 in a direction substantially at a right angle and at a slight angle with the inside edge 1 and outside edge 2 of each bar to form a tongue such as 6.

Preferably the outside edge 21 of each L-shaped slot 5 is not parallel with the outside edge 2 of its bar but is parallel with the axis of the plug to which it is to be attached and the outside edge 22 of the holding portion 15 of each disk is also preferably parallel with the said axis so that in assembling the bars and disks for a lining L on a form corresponding with the plug to which it is to be attached, when each bar is forced or driven in from the small end so that its tongue 6 can extend under the inside edge 23 of a holding part 15, there will be no tendency to pull the bar inward towards the axis of the plug although as shown in Fig. 9 such a construction can be used in some cases.

The inside edge 23 of the holding part 15 is also preferably parallel with or at a tangent to a cylinder, the center of which is the plug axis

and the outside edge 25 of each tongue 6 is parallel with the inside edge 23 of the cut out so that when entirely seated as shown in Fig. 6, there is a drive or forced fit between these parts whereby any radial movement, either outward or inward, by the bars is prevented.

The arm of the L-shaped recess as shown exaggerated at 45, Fig. 10, can taper so that the holding part 15 will be wedged in place.

As shown in Fig. 7 however, if a plastic material A is introduced into the pockets between adjacent disks and adjacent bars and the outside face 19 of the plug, I can provide recesses or holding holes 7 in the sides of or through the bars B or C into which this material A will be forced as at 8 whereby when it hardens, it will hold the separating material A in place and will also lock the disks D and bars B and C in place.

In the same way, as shown in Figs. 13, 14, 15 where wood W or a similar precut material for the separating members is used, if it swells when soaked, these precut members can be introduced when dry and then soaked so that part of them 50 will swell into holes such as 51 as shown in Fig. 8.

The tongues 6 of the bars C are of the same construction as of the bars B except that as these bars are of a greater depth, their tongues will be a little deeper to enter slots 40 but their outer edges will be the same.

The trapezium shape of the separators or separating material combined with the locking by nails N, or holes 51 or 7 and the stock 51 or 8 will hold the structure together even if, as shown in Fig. 12, there is not a tight fit between a tongue 6 and holding portion 15 of a disk.

The extra deep bars C not only prevent the lining L from turning but, on the same principle explained in patent to Schueler, No. 2,336,039, they will also help to hold the lining against radial displacement.

As shown in Fig. 11, the part 26 at the outside edge of the tip 27 of each tongue 6 may be at an angle so as to assist in seating the holding part of each tongue and the connecting or holding part 15 of a disk to register.

It will be noted that the bars as shown are to be driven in from the small end of the plug, the tips of the tongues therefore being directed towards the large end and it will be noted that the disks D, D, are in a plane perpendicular to the axis of the plug while the direction of the bars B and C are at an angle therewith.

I may take advantage of this condition where as in some cases, we wish to use preformed or precut separators such as shown at W in Fig. 15, which have a relatively narrow inside face 30, outside face 31, inwardly converging side faces 32 and ends 34 and 35 both of which conform to the angle between a disk and the outer surface 19 of a plug whereby if a nail such as N is driven through a disk into the end 34 that end will be held from springing out and the other end 35 will be held in a sort of a wedge shaped socket. This will lock the bars and disks in place.

As shown, each of these wooden separators has a part which extends at 36 and 37 over the outside of the outer rim 16 of a disk.

As shown in Fig. 14, this lining or jacket L omitting the extra deep bars C, C, can be used on a plug such as 60 having no slots 40, 40, but a smooth outer face 69. As a unit it can be slipped thereon or forced thereon to be held by friction or it may be fastened to the plug 60 by screws indicated by 61 or in any other way.

I find it convenient in assembling a jacket such as L on a suitable form, to put the disks such as D in place and then to drive the bars such as B or B and C in from the small end of the form to seat the tongues such as 6 under the holding parts 15 of the disks and, when all are in place, to shrink a ring 63 over the projecting tips 64 of the bars at the small end. A ring 62 at the large end can then be attached so as to stiffen the assembly of disks and bars. The wooden separators or preformed separators such as W can be put in place and held as by nails N or plastic material such as A can be poured or trowelled into the pockets between the bars and disks.

In some cases however, the rings 62 and 63 and the separating material can be entirely omitted as an assembly of disks and bars with or without rings 62 and 63 can be put together and will hold together if there is a perfect fit between the arms of the L-shaped recesses in the bars and the holding parts of the disks as shown in Figs. 6 and 9 or if they are wedged together as shown in Fig. 10.

Fig. 6 shows a smooth accurate joint between the L-shaped recesses and this holding part 15.

Fig. 9 shows an accurate joint between the faces 21 and 22 and between 25 and 23 along part of their faces, a part of the face 25 being slightly bevelled to help in seating.

In Fig. 11, the same construction is shown, there being a close accurate fitting joint between 21 and 22 and between 25 and 23.

In Fig. 10, as described, there is a distinct wedging action although of course the extent of the slopes is exaggerated in the drawing, while in Fig. 12 a clearance is shown between the faces 21 and 22 but a close joint between 25 and 23. With such a construction, separating members of some type, either preformed or plastic, are highly desirable, if not necessary, to hold the structure firmly together.

By disk, I mean a flat metal member which is of substantially greater diameter, namely in a radial direction from the axis of the plug, than its thickness, which would be the distance between its flat faces as measured in an axial direction. This word "disk" or the word "disks" is clearly intended to distinguish from a "band" or a "hoop," each of which is of greater width as measured in the direction of the plug's length, than its thickness as measured in a radial direction from the plug's axis and also to distinguish from an annular rod or wire of circular cross section.

I claim:

1. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned in aligned outside disk cut outs and extending outward beyond the outside rims of the disks, each bar having a plurality of L-shaped recesses forming tongues extending from its inside edge, each tongue extending through an inside cut out in a disk with the disk bar holding portion entering a bar tongue recess and engaging a tongue, each bar having a filling holding recess positioned in its

side between adjoining disks and there being two or more holding bars the inside edges of which extend radially inward beyond the inside edges of the other bars to enter slots in a Jordan plug; and filling positioned in the pockets formed by adjacent bars and disks, the filling entering the side filling holding recesses in the bars.

2. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned in aligned outside disk cut outs and extending outward beyond the outside rims of the disks, each bar having a plurality of L-shaped recesses forming tongues extending from its inside edge, each tongue extending through and engaging an inside cut out in a disk with the disk bar holding portion entering a bar tongue recess and engaging the top and bottom faces of the recess, each bar having a filling holding recess positioned in its side between adjoining disks and filling positioned in the pockets formed by adjacent bars and disks, the filling entering the side filling holding recesses in the bars.

3. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned in aligned outside disk cut outs and extending outward, each bar having a plurality of L-shaped recesses forming tongues extending from its inside edge, each tongue extending through an inside cut out in a disk with the disk bar holding portion entering a bar tongue recess and engaging a tongue, and there being two or more holding bars the inside edges of which extend radially inward beyond the inside edges of the other bars to enter slots in a Jordan plug.

4. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned in aligned outside disk cut outs and extending outward, each bar having a plurality of L-shaped recesses forming tongues extending from its inside edge, each tongue extending through an inside cut out in a disk with the disk bar holding portion entering a bar tongue recess and engaging a tongue.

5. The combination in a bodily transportable hollow truncated conical lining for a Jordan en-

gine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned with a close fit in aligned outside disk cut outs and extending outward beyond the outside rims of the disks, each bar having a plurality of L-shaped recesses forming tongues extending from its inside edge, each tongue extending through an inside cut out in a disk with the disk bar holding portion entering a bar tongue recess and engaging the top and bottom faces of the recess with a drive fit, each bar having a filling holding recess positioned in its side between adjoining disks and there being two or more holding bars the inside edges of which extend radially inward beyond the inside edges of the other bars to enter slots in a Jordan plug; and filling positioned in the pockets formed by adjacent bars and disks, the filling entering the side filling holding recesses in the bars.

6. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned with a close fit in aligned outside disk cut outs and extending outward beyond the outside rims of the disks, each bar having a plurality of L-shaped recesses forming tongues extending from its inside edge, each tongue extending through an inside cut out in a disk with the disk bar holding portion entering a bar tongue recess and engaging the top and bottom faces of the recesses with a drive fit, each bar having a filling holding recess positioned in its side between adjoining disks and plastic filling positioned in the pockets formed by adjacent bars and disks, the filling entering the side filling holding recesses in the bars.

7. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned with a close fit in aligned outside disk cut outs and extending outward, each bar having a plurality of L-shaped recesses forming tongues extending from its inside edge, each tongue extending through an inside cut out in a disk with the disk bar holding portion entering a bar tongue recess and engaging a tongue with a drive fit, and there being two or more holding bars the inside edges of which extend radially inward

beyond the inside edges of the other bars to enter slots in a Jordan plug.

8. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned with a close fit in aligned outside disk cut outs and extending outward, each bar having a plurality of L-shaped recesses forming tongues extending from its inside edge, each tongue extending through an inside cut out in a disk with the disk bar holding portion entering a bar tongue recess and engaging a tongue with a drive fit.

9. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned in aligned outside disk cut outs and extending outward beyond the outside rims of the disks, each bar having a plurality of L-shaped recesses forming tongues extending from its inside edge, each tongue extending through an inside cut out in a disk with the disk bar holding portion entering a bar tongue recess and engaging a tongue, each bar having a filling holding recess positioned in its side between adjoining disks and there being two or more holding bars the inside edges of which extend radially inward beyond the inside edges of the other bars to enter slots in a Jordan plug; and hardened plastic filling positioned in the pockets formed by adjacent bars and disks, the hardened plastic filling entering the side filling holding recesses in the bars.

10. The combination in a bodily transportable hollow truncated conical lining for a Jordan engine plug; of a plurality of annular disks of different diameters, each positioned in a plane perpendicular to the axis of the lining, each disk having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned with a close fit in aligned outside disk cut outs and extending outward, each bar having a plurality of L-shaped recesses forming tongues extending from its inside edge, each tongue extending through an inside cut out in a disk with the disk bar holding portion entering a bar tongue recess and engaging the top and bottom faces thereof with a drive fit.

11. The combination in a bodily transportable hollow truncated conical lining for a Jordan engine plug; of a plurality of annular disks of different diameters, each positioned in a plane perpendicular to the axis of the lining, a cross section of the rim of each disk being of a greater

radial height than its circumferential width, having a plurality of outside radial bar cut outs extending radially inward from its outer rim and inside radial bar cut outs extending radially outward from its inner rim, each in line with an outside bar cut out, there being a bar holding portion between the cut outs; with a plurality of substantially straight bars each positioned with a close fit in aligned outside disk cut outs and extending outward, each bar having a plurality of L-shaped recesses forming tongues extending from its inside edge, each tongue extending through an inside cut out in a disk with the disk bar holding portion entering a bar tongue recess and engaging the top and bottom faces thereof with a drive fit.
